DESIGN FOR AN EYEGLASS FRAME

George Donald Smart, Los Angeles, Calif.

Application December 29, 1947, Serial No. 143,422

Term of patent 14 years

(Cl. D57—1)

To all whom it may concern:

Be it known that I, George Donald Smart, a citizen of the United States, residing at Los Angeles, in the county of Los Angeles and State of California, have invented a new, original, and ornamental Design for Eyeglass Frames, of which the following is a specification, reference being had to the accompanying drawing, forming part thereof.

Figure 1 is a perspective view of an eyeglass frame, embodying my new design;

Fig. 2 is a view in side elevation of the same; and

Fig. 3 is a partial top plan view of the same.

I claim:

The ornamental design for an eyeglass frame, as shown.

GEORGE DONALD SMART.
